UNITED STATES PATENT OFFICE

170,007

DOLL

Marjorie M. Collins, Ottawa, Kans.

Application October 11, 1952, Serial No. 21,809

Term of patent 3½ years

(Cl. D34—4)

To all whom it may concern:

Be it known that I, Marjorie M. Collins, a citizen of the United States, residing at Ottawa, in the county of Franklin and State of Kansas, have invented a new, original, and ornamental Design for a Doll, of which the following is a specification, reference being had to the accompanying drawing, forming a part thereof.

Fig. 1 is a front elevational view of the doll, showing my design; and

Fig. 2 is a side elevational view thereof.

The portion of the design not shown is substantially plain.

I claim:

The ornamental design for a doll, as shown and described.

MARJORIE M. COLLINS.
